UNITED STATES PATENT OFFICE.

THOMAS TURTON JONES, OF LIVERPOOL, ENGLAND.

SHIP'S CONSTRUCTION.

1,167,503.

Specification of Letters Patent.

Patented Jan. 11, 1916.

Application filed May 1, 1913. Serial No. 764,957.

To all whom it may concern:

Be it known that I, THOMAS TURTON JONES, a subject of the King of England, residing at 656 Royal Liver Building, Pier Head, Liverpool, in the county of Lancaster, England, have invented new and useful Improvements in or Connected with Ships' Construction, of which the following is a specification.

10 This invention has reference to the construction of ships; and has chiefly for its object to provide a construction which, when the ship is struck or damaged by collision or similar accident, shall limit or 15 diminish the degree of loss of stability or safety of the ship due thereto, relatively to that they are liable to, if constructed according to the present or usual system. Or in other words, its chief object is to render 20 such ships safer generally, and less liable to be sunk by being struck by or colliding with another ship or object, or like accident.

In a metal ship of the type to which the present invention is to be applied, the sides 25 and bottom, say up to or some distance above the water level of the ship, are formed or comprised of a plurality of large tubes, or tubular or chamber construction, and extend for the full length of the ship, or for 30 major portion of it, say, and all interconnected and provided at intervals with transverse diaphragms or partitions (say from 20 to 40 feet apart), and with interspaced stiffening or strengthening members be- 35 tween the diaphragms pitched apart at comparatively short intervals.

According to this invention, on the inside 40 of the web-frames, and other frames, the inner plating or skin, constituting the true and vital shell of the ship, comes; that is, it is made stronger than the outer plating of the tubular or chambered construction, which constitutes the vulnerable part or shell. Thus in this system, the vital part 45 (that is the real shell plating) is constructed with the web-frames (and other usual or ordinary frames) outside the vital shell plating; and connected with these parts is the vulnerable portion, consisting of or com- 50 prising the outer plating or parts of the longitudinal tubular members, to which the outer shell plating is not in some cases directly attached.

The invention will be further described 55 with reference to the accompanying drawings, which illustrate it.

In these drawings, Figures 1 and 2 are vertical cross sections, and Figs. 1^A and 2^A are plans in section of same, respectively, through the side, showing the ship's construction. Fig. 3 is a vertical section of the construction shown in Fig. 1 taken at the line A A Fig. 1^A; and Fig. 4 is a plan in section of a ship's side showing a slight modification of the construction shown in Figs. 1 and 1^A, and of which Fig. 3 is also a vertical section at the lines B B.

Referring to the drawings, 1 represents the horizontal tubular members, and 2 the transverse diaphragms in them, disposed at 70 intervals apart, forming water tight chambers such as described.

3 represents the outside shell plating and 4 is the inner or main vital shell plating.

5 represents the web-frames on the inner 75 side of the tubular members 1; and, as shown, the inner or vital shell plating or skin 4 (which extends the full girth from the center line of the ship, up to and above the water line) is on the inside of these 80 frames; to which of course they will be directly attached; and all the parts will be suitably attached to one another as will be well understood to those skilled in ship- 85 building.

The two skins may be 4 to 5 feet apart in a big ship and the true skin 4 might be about 1" thick, and the outer skin or plating 3, might be say about $\frac{1}{2}$ " to $\frac{3}{4}$ "; and the true skin 4 will extend down to, or near 90 to, the tank tops, where it ceases, and then passes down through the bottom of the ship (and may constitute, if desired, a tank margin plate), and thence under the bottom, as shown. This true skin as shown in the 95 drawings, is indicated by a thick line; whereas the outer and vulnerable skin portion 3 is shown by a thin line. From the point where the true skin or shell passes from the inside of the ship to the outer, the 100 tank top plating 6 is preferably of the ordinary thickness, *i. e.* it is relatively thin to that of the true skin.

The upper deck 7 is of water tight construction, or constitutes a watertight deck; and this may be assumed to be what is called in a big ship, the "upper deck"; and below this, is a "middle deck" 8; and again below that a "lower deck" 9. Between this deck 7 and the bottom, the frames of the ship 110 come; and they are inclosed, as stated, on the outside by the plate 3.

In the side construction the horizontal plates 10 form the longitudinal diaphragms between the tubes 1, *i. e.* constitute the bottom of one tube, and the top of the next tube 5 below; and in some cases all of these plates may be imperforate throughout, while, in other cases they may have parts cut out of them, making large holes; or some of them may be so perforated, and others imperforate, according to the requirements in the 10 ship to be provided with the improvements hereunder. These plates or diaphragms 10 will be fastened to the two skins 4 and 3 by angle bars or other suitable attachments.

15 With regard to the frames of the ship, these in modifications shown in Figs. 1 and 1^A, extend from the end of the floors 11 (which in the case shown extend up beyond the part of the skin plate 4 connecting the 20 inner and outer parts of this skin); and they consist of inner web-frames 5, and ordinary frames 12, fastened to the inner skin 4 only; while the outer skin 3 between the plate 4 and the deck 7, is stiffened by vertical 25 frames 13; and at certain distances in this modification (and in other constructions hereunder), the special diaphragms or frames 2 extend between the inner and outer skins, and are fastened in a water tight 30 manner with these skins, and constitute combined vertical water tight diaphragms and web-frames. These water tight diaphragms 2 will be spaced apart, in a big ship like the 35 "Olympic", about 30 feet from one another; while the web frames 5 will be about 10 feet from one another, and from the diaphragms 2. The distance apart of the frames 12 is about 30 inches; and the outer frames 13 are the same distance apart.

40 In the modification shown in Figs. 2 and 2^A, all the frames 5 between the water tight frames 2, are a species of web-frame; and they will also be perforated, as shown. The water tight diaphragm frames 2, should in 45 this, as in other cases, be much thicker than the web-frames 5, namely about $\frac{3}{4}$ of an inch in the former, and $\frac{1}{2}$ of an inch in the latter.

The construction shown in Fig. 4 is the same as that shown in Figs. 1 and 1^A, with 50 the exception of the modifications in respect of the web-frames 5, which in this case are

carried right across from the skin 4 to the skin 3, to both of which they are attached in any suitable way, but not in a water tight manner; and they may be perforated with 55 holes, as indicated in Fig. 2.

With regard to the construction in Figs. 1 and 1^A, the frames 12 and 13 lying midway between the web-frames 5, and a web-frame and a diaphragm 2, at their upper parts, 60 may be connected together by a plate, and fastenings, say to the depth of one of the tubes 1. This besides being a strengthening of the structure, enables a ship to be more easily built. The other remaining alternate 65 frames 12 and 13 will have knee plates and fastenings, as 14, fastening them together under each horizontal diaphragm 10.

As to these modifications, the use or adoption of one or other, or the combination of 70 them, in building a ship, will depend on the greater suitability of one or the other, and the requirements in each case.

With regard to the ordinary frames 15 of the ship, above the deck 7, these may be 75 scarfed to the frames 13, or 5 as the case may be; and in some cases may be strengthened by brackets extending between them and the deck 7. In all cases, the frames and web-frames may be constructed square off, *i. e.* 80 of right angle section, from the inner skin.

What is claimed is:—

A metal ship's construction comprising sides of tubular construction having thick 85 inner shell plates 4 and comparatively thin outer shell plates 3, and being fitted with vertical diaphragms or partitions 2 spaced at long intervals, and forming vertical water tight diaphragms between the shell plates 4 and 3, and with intervening frames 5, of 90 relatively light, and of non-water tight construction, and attached to the inner shell 4, and to the outer shell 3; substantially as described.

In testimony whereof I have signed my 95 name to this specification in the presence of two subscribing witnesses.

THOMAS TURTON JONES.
